PRESSING MACHINE

Angus F. Hanney, Norwood, Ohio, assignor to The American Laundry Machinery Company, Cincinnati, Ohio, a corporation of Ohio

Application August 24, 1933, Serial No. 686,563

9 Claims. (Cl. 68—9)

This invention relates to a timing device for machines where an operation is to be maintained for a predetermined time and then automatically released.

5 An object of the invention is to provide simple mechanism for maintaining for a given length of time a power application such as the final pressure between the coating members of a press, and for thereafter automatically releasing the power.

10 Other objects and advantages will appear to those skilled in the art from the following specification and description of the drawings and the essential features of which are summarized 15 in the claims.

15 In the drawings, Fig. 1 is a side elevation somewhat diagrammatic in form showing the timing mechanism applied to a laundry press; Fig. 2 is a partial section along the lines 2—2, of Fig. 1; 20 Fig. 3 is a partial elevation of the release mechanism of Fig. 1; while Figs. 4 and 5 are two views of the timing device in a slightly modified form as applied to a press operated by one cylinder in contradistinction to the press of Fig. 1 which is 25 operable by two cylinders.

25 While my timing mechanism might be applied to any machine where power is to be applied for a pre-determined time interval and then released, I have chosen to illustrate the device applied to a press such as is adapted for use in 30 garment or laundry work. A plurality of such presses is commonly operated in tandem or in series, in which case one press is actuated in a press-opening direction when another machine 35 is actuated in press-closing direction. Such operation has various disadvantages. For instance, arranging the lay of the work on one press may take longer than the pressing operation on another press, under which circumstances the 40 closed press should be opened before the other press is ready for closing. Also, if there are more than two presses in series it may be desirable to open one press at a certain time after its closing, irrespective of what may be happening at other 45 machines in the series. Again, various articles require different pressing times and my device permits an adjustment of the time interval during which the press remains closed so that it 50 may be adapted to a variety of work.

55 My device is illustrated in connection with a press having power means for closing the press and release means for causing opening of the press, although it might be used with a manually closed press. The release means is subject to control by a movable abutment having a pre-de-

termined pressure against one face and having its opposite face subjected to a fluid pressure which is gradually built up until it overcomes the first named pressure and causes actuation of the release means. In the present embodiment, 5 the fluid pressure is conducted to a container or pressure reservoir which communicates with a face of the movable abutment, and the flow of fluid pressure into the container is regulated by means of a pressure regulator and a restricting 10 valve so that the time required to build up a fluid pressure in the container sufficient to move the abutment may be varied within a wide range. Preferably also, fluid pressure is admitted to the 15 container or pressure reservoir at the same time that the power is applied to the motor for closing the press.

In Fig. 1 I have illustrated a press similar to that illustrated, described and claimed in the copending application of John P. Singiser, Serial 20 No. 683,322, filed August 2, 1933, and having associated therewith control mechanism similar to that described and claimed in my copending application, Serial No. 683,814, filed August 5, 1933. Therefore, only sufficient description will be given 25 of the press and its control mechanism to permit an understanding of my improved timing device.

The press comprises a frame 10 supporting a fixed head 11 and a bed 12 movable into and out 30 of registration with the head. The structure which permits this registering movement of the bed comprises a bed-supporting carriage 13 having rollers 14 which travel upon rails 15 mounted on the press frame. The power means illustrated 35 for causing the registering movement comprises a fluid motor having a cylinder 16, a piston 17 and a piston rod 18, which is connected to the bed by means of link 19, cranks 20 and 21, rigid with and pivoting about shaft 22, and link 23 40 connected to the bed carriage. Movement of the piston 17 forwardly or to the right as seen in Fig. 1, causes movement of bed 12 into registration with the head 11. When the pressure in cylinder 16 is relieved, a spring 24, through a 45 suitable connection with shaft 22, returns the bed to its forward or open position. Final pressure is applied between the pressing members, after they reach registering position, by a second fluid motor having a cylinder 25, a piston 26 and 50 a piston rod 27 adapted to move upwardly and contact a stem 28 downwardly extending from the bed 12 through a bearing in the carriage 13. The piston rod 27 contacts the stem 28 when the 55 parts are in registration and raises the bed

against the head. Upon release of pressure beneath piston 26 the bed and its associated parts move downward due to their weight.

The control mechanism for the supply of fluid power to cylinder 16 comprises a combined inlet and exhaust conduit 29 connected by inlet valve 30 and conduit 31 to the main pressure supply conduit 32, and connected by means of exhaust valve 33 and conduit 34 to the atmosphere. These inlet and exhaust valves are actuated by a cam 35 mounted on a shaft 36 provided with a control handle 37 in a position accessible to the operator. In the position shown in Fig. 1, valve 30 is closed and valve 33 is opened to the atmosphere while the press members remain in their open position. Movement of the cam 35 downwardly by actuation of the control handle reverses the position of valves 30 and 33, thus closing the exhaust conduit 34 and admitting fluid pressure through conduit 31 and valve 30 to conduit 29 and cylinder 16. The bed thereupon moves into registration beneath the head. Upon the parts reaching registering position the follower 38 on an interlock arm 39 enters a notch 40 in cam 41 mounted on the bed carriage, impelled by spring 42 acting through suitable linkage. This interlock arm is connected by link 43, bell crank 44, link 45, bell crank 46, and link 47 with lever 48 which operates the valves controlling the flow and exhaust of fluid pressure to and from cylinder 25. Inlet valve 49 admits fluid pressure through conduit 50 to a combined inlet and exhaust conduit 51 leading to cylinder 25. Exhaust valve 52 in turn is adapted to connect conduit 51 with exhaust conduit 53 leading to the atmosphere. An inspection of Fig. 1 shows that movement of follower 38 into cam notch 40 moves bell cranks 44 and 46 in a clockwise direction and moves lever 48 in a direction to close valve 52 and open valve 49 thus admitting fluid pressure beneath piston 26, which will raise the bed against the head for the pressing operation.

For releasing the power at the close of the pressing operation fluid pressure actuated release cylinder 54 is provided having a piston rod 55 adapted to move a release lever 56 which has connections for moving the valves of the two motors in a press-opening direction. For actuating the valves controlling motor 16, shaft 36 is provided at its inner end with a flanged collar 57 which, in its operated position, is shown in broken lines at 58 of Fig. 3. The lever 56 is adapted to contact the flanged collar and return it to its full line position in Fig. 3, thus closing valve 30 and opening valve 33 to relieve the pressure in cylinder 16. A second connection of the release mechanism is adapted to reverse the valves of motor 25. This comprises an arm 59 rigid with lever 56 which carries a pin 60 having a lost motion connection in slot 61 of the linkage assembly 45. When bell cranks 44 and 46 move in a clockwise direction, link 45 moves upward without any effect on lever arm 59 but with the result that pin 60 lies adjacent the lower end of slot 61. Actuation of the release piston rod 55 against lever 56 causes arm 59 to move downwardly, moving linkage assembly 45 in the same direction, thus causing counter-clockwise movement of bell crank 46, and through link 47 and lever 48 closing valve 49 and opening valve 52, relieving the pressure beneath piston 26 and permitting the bed to move downwardly as previously described.

The fluid pressure supply for release cylinder 54 may be controlled at the will of the operator, through valve 62 adapted to admit fluid pressure

through conduit 63 from the main supply line, which will then flow through conduit 64 to the release cylinder. The structure shown for actuating the release valve 62, comprises a push rod 65 adapted to contact the stem of valve 63, and in turn actuated by a finger guard 66 depending before the head in a freely swingable manner and adapted to be actuated by the operator's fingers if they are accidentally lying upon the bed as it moves toward registering position.

My improved timing mechanism, for opening the press automatically, comprises a second control valve 67 for the release mechanism. This valve is normally maintained closed by spring 68 and is adapted when open to admit pressure from conduit 69 to conduit 70, which leads to the release cylinder 54 through a check valve 71 which permits flow of fluid pressure only in the direction indicated by the arrow. Valve 67 is arranged to be operated by a movable abutment 72 which, in Fig. 1, comprises a diaphragm in a suitable casing 73 and having a plunger 74 adapted to contact the stem 75 of valve 67. Pressure for actuating the diaphragm 72 accumulates in a container or pressure reservoir 76 which receives its supply of fluid pressure through conduit 77, pressure regulator 78, and an adjustable restricting valve 79. The pressure regulator 78 is of the type which maintains a constant pressure on the outlet side thereof in spite of varying pressures on its inlet side. A check valve 80 permits flow only in the direction shown by the arrow and this will occur, of course, only when the pressure in container 76 is greater than the pressure on the upper side of said check valve 80.

Fluid pressure is admitted to conduits 69 and 71 in a definite timed relation to the application of power to close the press. Preferably such pressure is admitted simultaneously with the application of fluid pressure beneath piston 26, and this is accomplished by a conduit 81 establishing communication between cylinder 25 and conduits 77 and 69, although conduit 69 might be connected to some other source. Thus, when pressure is applied to create final pressure between the pressing members, the fluid flows through conduit 81 and conduit 69 to valve 67, but is unable to pass said valve as it is yet in its closed position. At the same time, fluid flows through conduit 77, through pressure regulator 78, and valve 79 to container 76. This flow may be regulated by the pressure regulator and the valve 79, so as to control the time required to build up sufficient pressure in container 76 to actuate diaphragm 72 in a direction to open valve 67. Upon pressure building up to a point sufficient to overcome spring 68, fluid flows from conduit 69 through valve 67, conduit 70 and check valve 71, to release cylinder 54, thus opening the press regardless of the presence of the operator. When the press is opened and pressure is relieved beneath piston 26, pressure is also relieved in conduit 81, which permits check valve 80 to open, thus evacuating container 76 preparatory to the next cycle of operation.

In Figs. 4 and 5 I have illustrated a slightly modified form of timing device as applied to a press which is operable entirely by one fluid motor in place of the two motors illustrated in Fig. 1. Similar parts are similarly numbered with the characters having the suffix *a*, and only sufficient description will be given to permit an understanding of the operation of this press.

The piston rod 27a of motor 25a is provided with a saddle 82 having a pivoted connection with 75

arm 83, which in turn is pivoted to the frame at 84. The forward end of this arm is moved downwardly by movement of the piston rod 27a and its associated saddle 82 in an upward direction. Arm 83 presses downwardly on follower 84a, which is carried by an arm 85 which is pivoted to the frame at 86 and which has a link 87 connecting it with the carriage 13a for causing the registering movement of the bed 12a. The pressing members are shown in open position in Fig. 4 and in closed position in Fig. 5. In the latter case, the arm 83 has moved downward and the forward arcuate face 88 of arm 83 holds arm 85 in the position shown in Fig. 5 with the bed in registration with the head.

It will be understood that the first part of the movement of piston 26a and its associated piston rod and saddle causes movement of the bed into registering position, and thereafter further movement of piston rod 27a contacts stem 28a and lifts the bed to apply final pressure between the pressing members. Upon release of the pressure beneath piston 26a, the bed and associated parts move downward due to their weight and spring 89 returns the bed to its forward or open position. Arm 90 is pivoted to the frame at 91 and is pressed forward by compression spring 92 so that notch 93 engages follower 84 when the press is in its open position, thus holding the bed firmly in that position. The control valves 33a, 30a, are actuated by control handle 31a in a similar manner to similarly marked valves of Fig. 1, except that they control the flow of fluid pressure through conduit 29a to motor 25a which is the only motor necessary to operate the press of Figs. 4 and 5. In a similar manner release control valve 62a admits fluid pressure to release mechanism 54a which moves lever 56a into contact with flanged collar 57a to return the control valves to press-opening position.

The timing device illustrated in Figs. 4 and 5 comprises a container 76a to which pressure is admitted from cylinder 25a through conduits 81a and 71a, and regulating valve 79a, in a similar manner to that described in connection with Fig. 1. In this case, however, valve 67a is actuated by a piston 94 which is subjected to the fluid pressure in container 76a and is adapted to move the stem 95 of valve 67a in valve-opening direction when sufficient pressure has built up in container 76a to overcome spring 68a. Thereupon fluid pressure flows through conduits 81a, 69a, valve 67a, conduit 70a and check valve 11a to release mechanism 54a, thus operating the releasing mechanism which reverses the control valves, causing the press to return to its open position as previously described.

By adjustment of the pressure regulator 78 and the restricting valve 79 (or 79a), I find that the flow of fluid pressure to container 76 may be varied within very wide limits, so that the opening of the press may be timed at a longer or shorter interval after the closing operation as required by the character of the work.

It will thus be apparent that I have provided a timing mechanism which is very simple in operation, and which requires very few parts, and those parts are such that they do not easily get out of working order.

It is also apparent that when the power means for closing the press is a fluid motor such as motor 25 or 25a, the automatic initiation of the timing operation is extremely simple as the admission of fluid pressure to the operating motor 25 or 25a, automatically admits pressure through

conduit 81 or 81a to the timing mechanism and starts the running of the time interval which is necessary to build up pressure in the pressure reservoir.

What I claim is:

1. In a pressing machine, a fixed pressing member, a coacting pressing member movable laterally into and out of registration with said fixed member and into and out of pressing engagement therewith, fluid actuated power means for moving said movable member, conduit means controlling the flow of motive fluid to and from said power means and including an inlet valve and an outlet valve, an oscillatable shaft having cams thereon adapted to actuate said valves so that when either one is closed the other is open, a manual for moving said shaft in into-registration and into-engagement producing direction, fluid actuated timing means having a conduit connection with said conduit means whereby said timing means is supplied with fluid simultaneously with the supply to said power means, and an operative connection between said timing means and said shaft for moving the latter in out-of-engagement and out-of-registration producing direction when said timing means has completed its operation.

2. In a pressing machine, a fixed pressing member, a coacting pressing member movable laterally into and out of registration with said fixed member and into and out of pressing engagement therewith, fluid actuated power means for moving said movable member, conduit means controlling the flow of motive fluid to and from said power means and including an inlet valve and an outlet valve, an oscillatable shaft having cams thereon adapted to actuate said valves so that when either one is closed the other is open, a manual for moving said shaft in into-registration and into-engagement producing direction, a fluid actuated release motor for moving said shaft in out-of-engagement and out-of-registration producing direction, fluid supply means for said release motor including a pilot valve, fluid actuated timing means having a conduit connection with said conduit means whereby said timing means is supplied with fluid simultaneously with the supply to said power means, and an operative connection between said timing means and said pilot valve for opening the latter when said timing means has completed its operation.

3. A pressing machine as in claim 2, and including manually operable means independent of said timing means for moving said shaft in out-of-registration-producing direction.

4. A pressing machine as in claim 2, and including a finger guard located adjacent the path of travel of said bed into registration, said guard having an operative connection with said shaft for moving the latter in out-of-registration producing direction.

5. A pressing machine as in claim 2, and including a second manual having an operative connection for opening said pilot valve independently of said timing means.

6. In a pressing machine, a fixed pressing member, a coacting pressing member movable laterally into and out of registration with said fixed member and into and out of pressing engagement therewith, fluid actuated power means for moving said movable member, conduit means controlling the flow of motive fluid to and from said power means and including an inlet valve and an outlet valve, an actuator having operative connections for moving said valves so that when

- either one is closed the other is open, a manual for moving said actuator in into-registration and into-engagement producing direction, a fluid actuated release motor for moving said actuator in 5 out-of-engagement and out-of-registration producing direction, fluid supply means for said release motor including a pilot valve, fluid actuated timing means having a conduit connection with said conduit means whereby said timing means is supplied with fluid simultaneously with the supply to said power means, and an operative connection between said timing means and said pilot valve for opening the latter when said timing means has completed its operation.
- 10 15 7. In a pressing machine, a fixed pressing member, a coacting pressing member movable laterally into and out of registration with said fixed member and movable into and out of pressing engagement therewith, a first fluid motor for causing said registering movement, a second fluid motor for causing said engagement movement, conduit means including an inlet and outlet valve for controlling the supply of motive fluid for operating each motor, first and second 20 actuators for the valves for the respective motors, each actuator being arranged to open either of its associated valves when the other valve is closed, a manual for moving said first actuator in into-registration-producing direction, means actuated by movement of said movable member into registry for moving said second actuator in into-engagement producing direction, fluid actuated timing means having a conduit connection with

25 said conduit means whereby said timing means is supplied with fluid simultaneously with the supply to said second motor, and an operative connection between said timing means and both of said actuators for moving the latter respectively in out-of-engagement and out-of-registration producing directions when said timing means has completed its operation.

30 8. A pressing machine as in claim 7, and including manually operable means for moving both of said actuators respectively in out-of-engagement and out-of-registration producing directions independently of said timing means.

9. In a pressing machine, a fixed pressing member, a coacting pressing member movable into and out of registration with said fixed member and into and out of pressing engagement therewith, power means for moving said movable member, power supply means therefor having a single control member movable in two directions, 20 manual means for moving said control member in into-registration and into-engagement producing direction, timing means having a power supply connection with said first-named power supply means whereby said timing means is supplied with power simultaneously with the supply to said power means, and an operative connection between said timing means and said control member for moving the latter in out-of-engagement and out-of-registration producing direction when said timing means has completed its operation.

ANGUS F. HANNEY.
